UNITED STATES PATENT OFFICE.

HENRY MORAN, OF LONDON, ENGLAND.

MECHANISM FOR ACTUATING CHANGE-SPEED GEARS.

Application filed October 6, 1927, Serial No. 224,409, and in Great Britain October 18, 1926.

This invention is for improvements in or relating to mechanism for actuating change-speed gears of that type comprising a plurality of sliders operatively connected to the 5 gears, and a single gear-change lever which can be moved to engage any one of the sliders and be thereafter given a further movement to cause the selected slider to move in an end-wise direction to effect engagement of a selected gear.

An important object of this invention is to provide an improved construction of mechanism for actuating change-speed gears of the type above specified comprising a selector 15 device so arranged that when it is desired to change the gear from neutral to an engaged position, or from one engaged position to another, such change can be arranged for in advance and then be brought about by operating 20 a single operating device whatever the desired new engaged position of the gear may be. Another important object of the invention is to obviate the to-and-fro movement of the usual manually-operated gear-change lever 25 and to substitute therefor a movement in one direction only of a lever, for engaging any desired gear, and a second movement in one direction only of a second lever, for restoring the gear to neutral. Conveniently, these two 30 levers will each disengage the clutch between the prime-mover and the gear-box before engaging or neutralizing the gear, and on returning, for example, under the action of a spring, to their original position will re-engage that clutch.

According to an important feature of the invention there is provided in or for a change-speed gear of the type specified, a gear selector, a yielding-connection between said selector and the gear-change lever which, upon operation of the selector, urges the said lever to engage or to remain in engagement with a selected slider, connections between said gear-change lever and a clutch-pedal which, when 45 the pedal is moved to disengage the clutch, causes the sliders to assume a "neutral" position at which time the said yielding-connection causes the gear-lever to engage or to remain in engagement with the selected slider, and a gear-pedal connected to said gear-change lever to shift the latter so as to engage the selected gear.

According to another important feature of the invention, there is provided for moving 55 the gear-change lever in either direction, a

pair of oppositely moving elements movable each from a neutral position into two controlling positions corresponding each to a desired setting of the change-speed gear and operating means (for example, said gear-pedal) 60 for moving said elements in opposite directions, said gear-change lever having combined therewith a member which can be connected to one or other of the said elements when in their neutral position by the said yielding- 65 connection.

According to a further important feature of the invention, the clutch-pedal is connected to said elements to move them to neutral position after the clutch has been disengaged and 70 wherein a gear-pedal is also combined with the elements to move them from neutral position into position to engage the selected gear and also temporarily to disengage the clutch during the engagement of said gear.

According to yet another important feature of the invention, the means for moving the gear-change lever comprises in combination two interconnected elements whereof one is movable relatively to the other into two controlling positions, which elements in each such position permit movement of the gear-change member to one end position and hold it against movement from neutral towards the other end position respectively, means (for 80 example, a selector device) for positioning said element at will in one or other of its two controlling positions, and operating means (e. g. a single member such as a pedal) which when moved in one direction, will shift said 85 gear-change member from the neutral position in accordance with the selected position of said elements.

Other features of the invention relate to selective mechanism, interconnecting means, 95 connecting device, and operating means aforesaid and will be described hereinafter and pointed out in the claims.

Two embodiments of the invention are diagrammatically illustrated by way of example 100 in the accompanying drawings, wherein:

Figure 1 is a diagrammatic side elevation partly in section, showing one form of gear-changing apparatus according to the invention with the gear-change lever in one operative position.

Figure 2 is a like view of the same apparatus when the gear-change lever has been shifted to neutral, and

Figure 3 is a like view of the apparatus 110

when the gear-change lever has been shifted from neutral to a second operative position;

Figure 4 is a vertical sectional end elevation taken on the bent-line 4-4 in Figure 1, 6 and

Figure 5 is a horizontal section taken on the line 5-5 in Figure 1;

Figure 6 is a side elevation showing another form of gear-changing apparatus according 10 to the invention;

Figure 7 is a sectional end elevation taken on the line 7-7 in Figure 6, and

Figure 8 is a sectional end elevation taken on the line 8-8 in Figure 6 showing the 15 pedals and clutch lever.

Like reference numerals designate like parts throughout the several views.

Referring to Figures 1 to 5, the invention will now be described with reference to a 20 change-speed gear on a motor-vehicle having a gear-change lever 22 that is mounted between its ends by a ball-joint and is arranged to move in an H-gate, not shown, and shift two sliders 23, 24 each from a neutral 25 position into two end positions to provide three speeds and reverse. Two elements in the form of bars or sliders 20, 21 are arranged to slide on the gear-box or other convenient part of the vehicle, horizontally one above 30 the other, towards and away from the lever 22. Assuming that these bars 20, 21 are in front of the gear-change lever 22 to which they can be operatively connected in the manner described hereinafter the front ends 35 of these bars are bent horizontally at right-angles to their length to provide lugs 25, 26 respectively, as shown in Figure 2. Towards the rear the bars 20, 21 have each a connecting point in the form of a recess 27, 28 respectively, cut in their adjacent faces.

The two bars are connected together at a 40 point between their ends by interconnecting or reversing means which may take various forms. As shown, two slots 29 are provided, 45 one in a lug on the top of the bar 20, and one in a lug at the bottom of the lower bar 21, and a link pivotally mounted in line with the meeting edges of the bars 20, 21 carries two pins 30, 31, one in each slot 29, so that 50 the forward movement of one bar causes a rearward movement of the other. Alternatively the interconnecting means may comprise a pinion meshing with toothing on the bars formed as toothed racks.

55 Operating means for shifting the sliding bars 20, 21 will now be described. A single member 40, 41 in the form of a pedal, hereinafter referred to as a neutral pedal, is fulcrumed at 42 below the front end of the bars 60 20, 21 and has a longer upstanding arm 40 and a shorter arm 41 at right angles thereto arranged to co-operate with a clutch-lever 43 on a clutch-shaft 44 for operating the clutch 65 of the transmission mechanism with the vehicle. The arm 40 has at the level of the

meeting edges of the bars 20, 21 a vertical slot in which a pin 45 is movable. This pin 45 is carried by a link 46 pivoted to the shorter arm 48 of a lever 47, 48 which is in the form of a pedal, hereinafter referred to 70 as a gear-pedal, and is fulcrumed on the neutral pedal at 49. The gear-pedal is held in its normal position, wherein the pin 45 is opposite the lug 25, by a coil spring 50 attached at one end to the neutral pedal and at its other end to the arm 48. When this gear-pedal is rocked against the action of its spring by placing a foot on the longer arm 47 the pin 45 is lowered so as to lie opposite the lug 26 on the lower bar 21. 75

80 A connecting device in the form of selector mechanism is arranged operatively to connect at will one or other of the connecting points or recesses 27, 28 in its neutral position with the gear-change lever 22. As 85 illustrated, this selector mechanism comprises a manually-operable crank 52 preferably provided with arresting means, for example of the kind described hereinafter, for arresting it at will in any one of four positions 90 situated 90° apart one from another. The crank-pin 53 pivotally carries the upper end of a vertical flat spring 54 shown as a compound spring carrying a solid block 55 near the middle of its length, which spring is pivotally connected at its lower end to a substantially horizontal flat-spring 56 also shown as a compound spring, at a point between its ends, preferably near the middle of its length. This lower spring 56 has one end pivotally connected to the gear-change lever 22 and carries at its other end a pin 57 which in an upper position of the springs 54, 56 can enter the recess 27 in the upper bar 20, and in the lower position of the said springs can enter the recess 28 in the lower bar. These 100 springs 54, 56 are arranged to flex at right-angles to one another; the upper spring 54 is movable up and down and also to-and-fro about a guide pin 58 extending through the 110 slot 59 in the block 55, and the lower spring 56 can rock bodily up and down about the upper end of the gear-change lever 22 as a fulcrum so that the pin 57 can move up or down from one recess to the other, and the 115 spring 56 can also move horizontally about either of the recesses 27, 28 as fulcrum and thereby rock the gear-change lever 22 from either of its two neutral positions into the 120 other.

When the crank 52 is rotated, the upper end of the spring 54 will be reciprocated and flexed, and will move the lower spring 56 up or down or sideways according to the part of the circular path along which the crank pin 125 53 is travelling. Assuming that the sliding bars 20, 21 are in their neutral position, as the crank-pin 53 moves towards the guide-pin 58, the lower spring 56 will be moved into engagement with the lower bar 21. Further 130

movement of the crank 52 into its lower position will tend to move the gear-change lever 22 over into its other neutral position to one or other side of the gate. It will thus be appreciated that when the gear-change lever is in neutral, the setting of the selector device determines which gear can be thrown in.

The gear-changing apparatus constructed as described above operates as follows:—

- 10 Assuming that the parts are in the positions shown in Figure 1 and it is desired to change gear by shifting the lever 22 in engagement with the slider 23 from the end position in which it is shown through neutral, as shown in Figure 2, to its opposite end position in engagement with the slider 24, as shown in Figure 3, the crank 52 will first be turned through 180° and the neutral pedal 40, 41 will then be depressed, whereby the 20 clutch lever 43 will be simultaneously rocked into its declutching position, as shown in full lines in Figure 2. During this movement of the neutral pedal, the pin 45 will drive the lug 25 of the top bar 20 and move the bars 20, 25 21 into their neutral position, as shown in Figure 2, in which position the recesses 27, 28 are in register and the gear-change lever 22 and sliders 23, 24 are also placed into neutral. At this time the lever 22 moves across 30 into engagement with the slider 24. When the neutral pedal is released it is returned by a spring 142 into its normal position, the clutch is temporarily engaged and the pin 57 at the end of the spring 56 snaps, owing to the 35 previous setting of the selector-device, into the recess 28 in the lower bar 21, as shown in Figure 2. The gear-pedal 47, 48 is then depressed, the pin 45 is lowered to a position opposite the lug 26, and on the gear-pedal 47, 48 being rocked further, the neutral pedal 40, 41 is also rocked into the position shown in Figure 3, the clutch is disengaged and the pin 45 drives the lug 26 of the lower bar 21 forwards, whereby the gear-change lever 22 45 and slider 24 are moved into their other end positions as shown in Figure 3. On the gear-pedal being released, both pedals will return into their normal position, shown in Figure 1, and the clutch is re-engaged.
- 50 The above-described gear-changing apparatus is particularly adapted for use in conjunction with mechanism for regulating the speed of an engine of a vehicle relatively to the road speed, preparatory to changing 55 gear, one form of such speed-regulating mechanism being described in my Patent Application No. 158,257 filed 31st December, 1926. When used in this manner, the actual change of gear is effected very smoothly at 60 the correct engine speed and by the simple operation of moving two pedals each in the same direction.

Referring now to Figures 6, 7 and 8, the elements aforesaid are in the form of a rotary disc 60 and a slotted plate 61 associated there-

with. The disc 60 is fast on one end of an axle 62 slidable endwise in a two-part bearing 63 and carrying between the two parts of the bearing a gear-change lever 22 adapted to engage the sliders 23, 24. The plate 61 is slotted in the form of an E, but modified to provide two middle cross-strokes 64, 65 that are spaced apart symmetrically between the top cross-stroke 66 and the bottom cross-stroke 67 of the E. Each of these cross-strokes runs into the down-stroke 68 situated towards one side of the plate which is connected by two rods 69, 70 to a neutral pedal 71 and a gear pedal 72, respectively. The opposite side of the plate 61 is provided with a ball 73 constituting part of a ball-joint connecting the plate to a selector device comprising a flat spring 54.

The disc 60 carries on its face adjacent the plate 61 three pins 75, 76, 77 which are shown, respectively in the slots 66, 64 and 68 of the plate 61 in the end vertical position of the latter. In this position of the elements 60, 61 the gear-change lever 22 is in one operative position. By sliding the plate 61 across the face of the disc 60 away from the pedals, the disc can be rotated so that its three pins all lie in the slot 68 and the gear-change lever 22 is in neutral. By lifting the plate 61 vertically into its other end position, the pin 77 will lie opposite the end of the slot 67, the pin 76 will lie opposite the slot 65, and the pin 75 will not be opposite any cross-slot of the E. Accordingly, if the plate 61 is then moved to the right as viewed in Figure 6, the gear-change lever 22 will rock into its other end position and thereby change the gear. The plate 61 is set into neutral with the three pins lying in the slot 68 by operating the neutral pedal 71, whilst the disc 60 is rotated by operating the gear pedal 72, and the disc 60 together with the plate is moved in the axial direction of the shaft 62 when the gear-change lever 22 is in neutral by means of the spring 54 of the selector device which also determines the vertical end position occupied by the plate 61.

The selector device comprises a tube 80 fast on the end of the spring 54 remote from the ball 73. This tube contains two coil springs 81, 82 arranged in a line and abutting at their outer ends against the ends of the tube. A slot extending along the whole length of the tube permits the pin 53 of a disc crank to lie between the inner ends of the coil springs 81, 82. This disc crank has in its periphery four recesses 83, spaced 90° apart, and a snap-catch 84 of any convenient construction is arranged to co-operate in turn with these recesses and hold the crank in any one of these four positions of adjustment. The spring 54 is movable up and down between a guide 85 situated at or about the middle of its length, so that the slotted plate 61 can be moved up and down into either of its

two end positions aforesaid. The lower end of the spring 54 can be flexed horizontally so as to move the disc 60 bodily in the direction of its shaft 62 into one or other neutral 5 position of the gear-change lever 22 for engaging one or other of the sliders 23, 24 according to the position of the crank-pin 53.

The neutral pedal 71 is mounted on a sleeve 90 journaled on an axle 91 mounted parallel 10 with the clutch shaft 44. The gear pedal 72 is fast on one end of this axle 91. The clutch lever 43 is connected by a link 92 to one arm 93 of a lever 93, 94 that is fulcrumed on the axle 91 between the two pedals 71, 72. This 15 arm 94 carries a cross-head 95 so arranged that when either of the pedals 71, 72 is rocked from its normal position in one direction to the limit of its movement the arm 94 is rocked and also the clutch-lever 43 so as to 20 disengage the clutch. Fast on the other end of the axle 91 is a lever-arm 96 that is engaged by a pin-and-slot connection with the gear-rod 70 whilst fast on the adjacent end of the sleeve 90 is an arm 97 that is engaged 25 by a pin-and-slot connection with the neutral rod 69.

Assuming that it is desired to change gear from one ratio to another, so that the slider 23 is moved from its one end position to the 30 other, the crank-pin 53 will be moved downwards through 90°, and on pressing the neutral pedal 71 the gear-change lever 22 will be placed into neutral, whereupon the slotted plate 61 will be lifted, so that the pin 77 lies 35 opposite the slot 67. If the gear pedal 72 is now depressed, the disc 60 will be rotated and shift the slider 23 to its other end position. The clutch will have been disengaged temporarily when either pedal is depressed as explained above. If the gear-change lever 22 40 is to be brought into engagement with the slider 24, the crank-pin 53 will have been set to such a position that on depressing the neutral pedal 71 the shaft 62 will move endwise 45 so that the lever 22 will move across the gate and come opposite the slider 24.

In this construction shown in Figures 6, 7 and 8 the slotted plate 61 is preferably accommodated between two discs 60, 98 into 50 which the three pins extend. It will be observed that in this construction the neutral pedal is extended beyond its axis of rotation and is there connected to the plate 61, so that both pedals 71 and 72 are pushed in order to 55 change the gear. The plate 61 preferably carries a rod 99 guided at its end remote from the plate by a slot slideable on the axle 91 between the rods 69 and 70, but some other form of guiding means for the plate may be provided if desired.

Both of the constructions of gear-changing mechanism described above are particularly adapted for use in conjunction with mechanism for regulating the speed of an engine of a vehicle relatively to the road speed, 65

preparatory to changing gear, for example, speed-regulating mechanism described in my prior patent application aforesaid. The speed-regulating mechanism would be thrown into action by the neutral pedal when fully depressed after disengaging the gear. It would remain in action so as to adjust the gear-shaft (driven by the engine through the clutch) to the correct engagement speed. It would then be thrown out of action by the gear-pedal at the end of its movement engaging the gear. The setting for the speed of the engine speed-regulating device can be effected by mechanism connected to the selector device crank-shaft in order that the appropriate engine speed for each gear may be chosen in connection with the road speed of the vehicle. If a cam is employed it would rotate in unison with the selector device crank-shaft. 70 75 80 85

In both of the constructions described above the gear-change lever is set by means of two operations, namely, (1) by moving the neutral pedal into its neutral position wherein either gear slider can be engaged through the usual gate by means of the above-described control mechanism comprising what may be termed a second gate and (2) by moving the gear-pedal in the same direction whereby one or other slider can be moved in one direction or the opposite direction as required; the said second gate determines in which direction the engaged slider shall be moved. The selection of the position of the gear-change lever in the usual gate and the adjustment of the second gate may be made when the change-speed gear is engaged, but change of this position and adjustment in either gate can only be effected when both of these gates are restored to neutral by operating the neutral pedal. 90 95 100 105

Various modifications may be made in the details of construction described above without departing from the scope of the invention. For example, hand-levers may be substituted for pedals. Moreover, in the case of a four-speed and reverse gear-box having three sliders, the selector may be arranged to choose one gear-slider for first and reverse, another for second and third, and another 110 for the fourth gears. 115

I claim:

1. In gear-selecting mechanism of the character described, the combination with a plurality of sliders for controlling the gears, and a single gear-change lever adapted to be moved to engage any one of the sliders, of a clutch pedal, connections between the gear-change lever and said clutch-pedal which restore the sliders to neutral position upon movement of the clutch-pedal to disengage the clutch, a gear selector device adapted to be operated to select a gear before the clutch is disengaged, a yielding connection between said selector device and the gear-change lever 120 125 130 135

which urges the gear-lever to engage or to remain in engagement with a selected slider when the sliders are in neutral position, and a lever connected to said gear-change lever to shift the latter thereafter to engage the selected gear.

2. In gear-selecting mechanism of the character described, the combination with a plurality of sliders for controlling the gears and a single gear-change lever adapted to be moved to engage any one of the sliders, of a clutch pedal, connections between the gear-change lever and said clutch-pedal which restore the sliders to neutral position upon movement of the clutch-pedal to disengage the clutch, a gear selector device adapted to be operated to select a gear before the clutch is disengaged, a yielding connection between said selector device and the gear-change lever which urges the gear-lever to engage or to remain in engagement with a selected slider when the sliders are in neutral position, and a lever connected to said gear-change lever to shift the latter thereafter to engage the selected gear and connections between said lever and the clutch to disengage the latter during engagement of the selected gear.

3. In gear selecting mechanism of the character described, the combination with a plurality of sliders for controlling the gears, and a single gear-change lever adapted to be moved to engage any one of the sliders, of elements which are adapted each to be connected to the gear-change lever, means for moving the said elements in opposite directions to restore the sliders to neutral position when the clutch is disengaged, a gear selector device adapted to be operated to select a gear before the clutch is disengaged, a yielding connection between said selector device and the gear-change lever which urges the said lever to engage or to remain in engagement with a selected slider when the sliders are in neutral position, means controlled by the said yielding connection for connecting the gear-change lever to a chosen one of said elements when the sliders are in neutral position, and means for moving the said elements from "neutral" position into position to engage a selected gear.

4. In a change-speed gear of the character described, the combination with a plurality of sliders for controlling the gears, and a single gear-change lever adapted to be moved to engage any one of the sliders, of a clutch pedal, a pair of elements which are each adapted to be connected to the gear-change lever, and which are movable by the clutch-pedal in opposite directions to restore the sliders to neutral position when the pedal is moved to disengage the clutch, a gear selector device adapted to be operated to select a gear before the clutch is disengaged, a yielding connection between said selector device and the gear-change lever which urges the said gear-change lever to engage or to remain in engagement with a selected slider when the sliders are in neutral position, connecting-means controlled by said yielding connection for connecting the gear-change lever to a chosen one of said oppositely moving bars, and a lever connected to said bars for moving the gear-change lever from neutral position into position to engage the selected gear.

said lever to engage or to remain in engagement with a selected slider when the sliders are in neutral position, means controlled by the said yielding connection for connecting the gear-change lever to a chosen one of the said oppositely-moving elements, and a gear-pedal connected to said elements for moving said gear-change lever from neutral position into position to engage the selected gear.

5. In a change-speed gear of the character described, the combination with a plurality of sliders for controlling the gears and a single gear-change lever adapted to be moved to engage any one of the sliders, of a clutch-pedal, a pair of elements which are each adapted to be connected to the gear-change lever and which are movable by the clutch-pedal in opposite directions to restore the sliders to neutral position when the pedal is moved to disengage the clutch, a gear selector device adapted to be operated to select a gear before the clutch is disengaged, a yielding connection between said selector device and the gear-change lever which urges the said lever to engage or to remain in engagement with a selected slider when the sliders are in neutral position, connecting-means controlled by the said yielding connection for connecting the gear-change lever to a chosen one of the said oppositely moving elements, a lever connected to said elements for moving said gear change lever from neutral position into position to engage the selected gear, and connections between said lever and the clutch to disengage the latter during the engagement of the selected gear.

6. In a change-speed gear of the character described, the combination with a plurality of sliders for controlling the gears and a single gear-change lever adapted to be moved to engage any one of the sliders, of a clutch-pedal, a pair of parallel bars which are each adapted to be connected to the gear-change lever, are mounted one beside the other, and are so operatively connected together as to cause them to move in opposite directions, connections between said bars and the clutch-pedal for moving said bars to restore the sliders to neutral position when the pedal is moved to disengage the clutch, a gear selector adapted to be operated to select a gear before the clutch is disengaged, a yielding connection between said selector and the gear-change lever which urges the said gear-change lever to engage or to remain in engagement with a selected slider when the sliders are in neutral position, connecting-means controlled by said yielding connection for connecting the gear-change lever to a chosen one of said oppositely moving bars, and a lever connected to said bars for moving the gear-change lever from neutral position into position to engage the selected gear.

7. In a change-speed gear of the character described, the combination with a plurality

of sliders for controlling the gears in a single gear-change lever adapted to be moved to engage any one of the sliders, of a clutch-pedal, a pair of parallel bars, which are adapted to be connected to the gear-change lever and are mounted one beside the other, a pivoted link having its ends connected one to each bar, connections between said bars and the clutch-pedal for moving said bars to restore the sliders to neutral position when the pedal is moved to disengage the clutch, a gear selector adapted to be operated to select a gear before the clutch is disengaged, a yielding connection between said selector and the gear-change lever which urges the said gear-change lever to engage or to remain in engagement with a selected slider when the sliders are in neutral position, connecting-means controlled by said yielding connection for connecting the gear-change lever to a chosen one of said bars, a second pedal fulcrumed on the clutch-pedal and acting, when depressed, to disengage the clutch and move the said bars to restore the gear from neutral position into position to engage the selected gear.

8. In a change-speed gear of the character described, the combination with a plurality of sliders for controlling the gears and a single gear-change lever adapted to be moved to engage any one of the sliders, of a clutch-pedal, a pair of parallel bars which are each adapted to be connected to the gear-change lever, and are mounted to slide one above the other and are so operatively connected together as to cause them to move in opposite directions, an abutment on each of said bars, an associated abutment movably carried by the clutch-pedal and adapted, upon movement of the clutch-pedal to disengage the clutch, to engage the abutment on the upper bar and cause the sliders to assume a neutral position, a gear selector adapted to be operated to select a gear before the clutch is disengaged, a yielding connection between said selector and the gear-change lever which urges the said lever to engage or to remain in engagement with a se-

lected slider when the sliders are in neutral position, connecting means controlled by said yielding connection for connecting the gear-change lever to a chosen one of said oppositely moving bars, and a second pedal that is connected with said associated abutment and is fulcrumed on the clutch-pedal and acts, when depressed, to move the latter abutment to cause it to act upon the lower bar to restore the gear from neutral position into position to engage the selected gear.

9. In a change-speed gear of the character described, the combination of a rotary gear selector, a flexible link connected towards one end to said rotary gear selector and adapted to be connected towards its opposite end to a gear controlling member and a guide-member for said flexible link positioned intermediate the ends of said link, which guide member constitutes a fulcrum for said link and also allows the link to move endwise during the rotary movement of the said gear selector.

10. In a change-speed gear of the character described, the combination of a rotary gear-selector, a crank pin thereon, a flexible link secured at one end thereto, a pivot for the resilient link which has a pin and slot connection therewith, a flexible bar operatively connected to the other end of said link for connection at one end to a gear-change lever and at its other end to either element of a pair of sliding elements.

11. In a change-speed gear of the character described, the combination of a rotary gear selector, a slidable and oscillatory link of flexible structure connected thereto, a flexible bar for connection at one end to a gear-lever and connected between its ends to said link, a pair of oppositely sliding elements that are operable by means of a pedal and have each a recess, and a pin carried by the said flexible bar and urged by the said link into the recess in one of the sliding elements when the said recesses are brought into register by relative movement of the said elements.

In testimony whereof I affix my signature.
HENRY MORAN.
